UNITED STATES PATENT OFFICE.

GEORGE W. OSBORN, OF CLEVELAND HEIGHTS, OHIO.

GAUGE-COCK WEIGHT.

Application filed July 29, 1922. Serial No. 578,508.

To all whom it may concern:

Be it known that I, GEORGE W. OSBORN, a citizen of the United States, and resident of Cleveland Heights, in the county of Cuyahoga and State of Ohio, have invented certain new and useful Improvements in Gauge-Cock Weights, of which I hereby declare the following to be a full, clear, and exact description, such as will enable others skilled 10 in the art to which it appertains to make and use the same.

The objects of this invention are to provide adjustable features for a self closing gauge cock for a steam boiler, of the type 15 which is closed by a weight. The provision of adjustable features in this device makes it possible to take up the wear upon the valve pencil as fast as it occurs, and a sufficient number of adjustments are provided 20 to take up the entire possible wear of the pencil, thereby making the device much safer, and more economical in use, also the construction permits the adjustment of the arm of the weight to be made without re- 25 moving the weight from the valve stem, thereby preventing the operator from being injured by escaping steam.

The invention comprises a quick acting screw threaded valve stem, adjustable in the 30 body of the gauge cock, the outer end of which passes through the arm of a weight and it includes also an arm having an opening through which the said stem passes, and a recess having an inclined side wall and 35 countersunk in the inner face of the arm, the side wall of said recess being provided with projections having inclined sides, and said valve stem being provided with a multiple number of radial and outwardly tapered 40 projections or teeth having inclined sides which can be brought in turn, by revolving the weight into engagement in the grooves between said projections in the side wall of said recess.

45 It includes clamping means for securing the arm of the weight in adjusted position upon said valve stem.

The invention is illustrated in the accompanying drawings, hereinafter more fully 50 described, and specifically pointed out in the claims.

In these drawings, Fig. 1 is a longitudinal section of the valve and stem, Fig. 2 is a side elevation showing the weight and arm attached thereto. Fig. 3 is a perspective of 55 the weight and arm, Fig. 4 is a perspective

of the valve stem, and Fig. 5 is a vertical transverse section through the arm of the weight and recess therein showing the inter-engaging projections on the valve stem and 60 wall of said recess.

In these views A. is a screw threaded valve stem, B. is the weight and C. is the arm.

The valve stem is provided with a reduced outer end D. which passes through a circular opening E in the arm C and engages the 65 wall thereof.

A circular recess F is formed in the inner side of said arm which comprises an enlargement of said opening E. 70

Upon the longitudinal side of said recess are arranged a plurality of projections or teeth G. G. preferably six in number. In the grooves between these teeth are engaged a multiple number of teeth H. H. the latter 75 teeth being preferably twice as many in number, said teeth G. G. projecting longitudinally from a flange or shoulder which terminates the screw threaded inner portion of the valve stem. 80

A clamping nut J. upon the outer end of the reduced portion of the valve stem forces this shoulder against the inner face of the arm, and retains the arm in adjusted positions. 85

The teeth H. are preferably made of such length as to engage the inner shoulder K, between the bearing E and the recess F. thus making the connection rigid. 90

This construction provides for the adjustment of the weight in many positions and since the recess F is shallow the arm can be withdrawn from contact with the teeth H, without removing the arm from the reduced end of the valve stem, thus protecting the 95 operator from escaping steam.

L is the valve, casing M. is the valve seat and N. is the removable valve pencil which is made of soft metal so as not to injure the valve seat. Since this pencil wears rapidly 100 when pressed against the seat by the weight, it is necessary to provide the adjusting means described.

Having described the invention, what I claim as new and desire to secure by Letters 105 Patent is:

1. In a self-closing gauge cock, a valve casing, a screw-threaded valve stem rotatable therein, an arm thereon, rotatable therewith, a weight on said arm, said arm provided with an opening through which said valve stem passes, said opening being enlarged at 110

- the inner side of said arm to form a recess having an inclined side wall, spaced bevelled projections upon the inclined wall of said opening, and spaced and bevelled projections upon said valve stem, engageable in corresponding grooves formed by the projections upon said inclined wall, permitting quick angular adjustment of said arm and weight upon said valve stem, and a slight amount of movement thereof along said stem, the outer portion of the stem forming a bearing upon which said arm is withdrawable and rests while angular adjustment thereof is being made.
2. In a self-closing gauge cock, a valve casing, a screw-threaded valve stem rotatable therein, an arm thereon, rotatable therewith, a weight on said arm, said arm provided with an opening through which said valve stem passes, said opening being enlarged at the inner side of said arm to form a recess having an inclined side wall, spaced bevelled projections upon the inclined wall of said opening and spaced and bevelled projections upon said valve stem, engageable in corresponding grooves formed by the projections upon said inclined wall, permitting quick angular adjustment of said arm and weight upon said valve stem, and a slight amount of movement thereof along said

stem, the outer portion of the stem forming a bearing upon which said arm is withdrawable and rests while angular adjustment thereof is being made, and means for clamping said arm upon said valve stem.

3. In a self-closing gauge cock, a valve casing, a screw-threaded valve stem rotatable therein, an arm thereon, a weight on said arm, said arm provided with an opening through which said valve stem passes, a clamping nut upon the outer extremity of said valve stem, said valve stem provided with an annular shoulder, and with radial teeth outwardly tapering from said annular shoulder, and said arm provided with a recess about said opening on its inner side, the wall of said recess being inclined to correspond with the outwardly tapered teeth, and radial teeth inwardly extending from said wall and having inclined sides, said teeth in said recess being engageable in the corresponding grooves formed by the teeth upon said valve stem.

In testimony whereof, I hereunto set my hand this 4th day of January 1922.

GEORGE W. OSBORN.

In presence of—

CHAS. F. SIFE,
W.M. M. MONROE.
